PUMP

Elek Benedek, Milwaukee, Wis., assignor to The Hydraulic Press Manufacturing Company, Mount Gilead, Ohio, a corporation of Ohio

Application March 16, 1931, Serial No. 522,895

7 Claims. (Cl. 103—37)

This invention relates to variable delivery multiple piston pumps for use primarily in high pressure hydraulic power transmission systems.

Present commercial forms of pumps for this purpose ordinarily include a cylinder barrel and coacting impeller relatively adjustable to vary the length of the piston strokes and to thereby regulate the rate of pump delivery by regulating pump displacement. In such pumps the relatively adjustable parts are subjected not only to severe hydraulic loads, but also to severe mechanical loads, both of which increase directly as the hydraulic pressures increase and the combined effect of which is to impose a limit upon the hydraulic pressures which may be safely employed.

One object of the present invention is the provision of a variable delivery multiple piston pump capable of operation at pressures considerably higher than those employed in present commercial forms of variable displacement pumps. This I have accomplished by a novel combination and arrangement of parts which does not require adjustment or variation in the piston stroke, so that the piston driving means and coacting parts may be more sturdily constructed and mounted to better withstand the higher pressures, the variation in delivery being effected by auxiliary means adjustable to utilize variable portions of each piston stroke.

Another object is the provision in a multiple piston pump of valve means adjustably operable to utilize variable portions of each piston stroke and to bypass the liquid discharged from each pump cylinder during the remaining portion of each piston stroke.

Another object is the provision in a multiple piston pump of hydraulically balanced valve means for the purpose mentioned.

Other more specific objects and advantages will appear from the following description of an illustrative embodiment of the present invention.

In the accompanying drawings:—

Figure 1 is a transverse sectional view of a pump constructed in accordance with the present invention. This view is taken on the section line 1—1 of Figs. 2 and 3.

Fig. 2 is a longitudinal sectional view on the line 2—2 of Fig. 1.

Fig. 3 is a horizontal sectional view on the line 3—3 of Fig. 1.

Fig. 4 is a sectional view, on a larger scale, of the valve mechanism shown in Fig. 1.

Figs. 5 and 6 are sectional views on the lines 5—5 and 6—6 of Fig. 4, respectively.

Figs. 7, 8, 9 and 10 are sectional views, on a larger scale, of one of the cams shown in Fig. 3, these views being taken on the lines 7—7, 8—8, 9—9, and 10—10, respectively.

The pump shown is enclosed within a housing comprising a hollow base portion 10, constituting a liquid reservoir, an intermediate upright portion 11, and a cover portion 12. A large base casting 13, stationarily mounted in the base portion 10, supports a plurality of upright frames 14, which together provide a rigid support for a heavy crank shaft 15. In this instance the crank shaft is provided with a plurality of concentric bearing disks 16 individually journaled in anti-friction bearings 17 mounted in the upper ends of the frames 14. The crank shaft 15 is driven by an extension shaft 18 formed integral with an end disk 16.

The several upright frames 14 also form guides for a series of slide blocks 19, vertically reciprocable therein and individually driven from the crank shaft 15 through connecting rods 20. Each connecting rod shown terminates in a substantially flat head 21 which bears against a large trunnion pin 22 rotatably seated within one of the blocks 19 and extending crosswise thereof (Figs. 1 and 2). Each pin 22 is slotted to receive an ear 23, which projects axially from the head 21, and which is retained within the pin 22 by a transverse locking pin 24.

Each slide block 19 is mechanically connected to one of the plurality of pump pistons or plungers 25 preferably in such manner as to permit self-alignment of each plunger in its cooperating cylinder bore 26. In this instance each block 19 is socketed to receive the convex head 27 of its coacting plunger 25, the head 27 being yieldably retained against the base of the socket by a spring 28 secured in place by a locking ring 29.

The several cylinder bores 26 in the base casting 13 communicate, respectively, with transverse bores 30, which extend horizontally through the casting. A chamber 31 in each bore 30 communicates with a channel 32, which extends longitudinally of the casting 13 and communicates with the pump discharge pipe 33; and a chamber 34 in each bore 30 communicates with another longitudinal channel 35 which communicates with the pump inlet pipe 36.

A plunger type valve 37, having cylindrical end portions 38 and 39 is longitudinally reciprocable in each bore 30. End portion 38 controls communication between the bore 26 and chamber 31, and end portion 39 controls communication between the bore 26 and chamber 34, so that with

the valve in the right extreme position of Fig. 1, bore 26 communicates with the discharge passage 32, and when the valve is shifted into a left extreme position, bore 26 communicates with the 5 intake passage 35. In the intermediate position, shown in Fig. 4, both passages 32 and 35 are disconnected from the bore 26.

It will be noted that the hydraulic pressure within that portion of each valve between the end 10 heads 38 and 39 acts equally in opposite directions on said heads so that the valve is hydrostatically balanced longitudinally. It will also be noted that the hydraulic pressure within the intake and discharge passages 34 and 32 is equally 15 distributed about the end heads, 39 and 38, respectively, so that each valve is also hydrostatically balanced radially. Each valve is thus freely movable irrespective of the degree of hydraulic pressure applied thereto, an important consideration 20 in high pressure pumps of the type described.

The several valves 37 are actuated in properly 25 timed relation by appropriate means such as individual cams 40 on a cam shaft 41, the cam shaft being driven from the crank shaft 15, at 30 crank shaft speed, through an intermediate shaft 42 and suitable gearing 43 and 44. Each valve is provided at one end with a cam roller 45 which is held against its coating cam by a spring 46 at the other end of the valve.

The cam shaft 41 is journalled in appropriate 35 brackets 47 and 48 in which it is longitudinally shiftable to vary the effect of the several cams upon the respective valves. Although various means, either manual, mechanical, or hydraulic, 40 may be employed for effecting lengthwise adjustment of the cam shaft, I have disclosed a satisfactory hydraulic means for the purpose. In this instance a reduced end 49 of the cam shaft is fitted in a bore 50 into which fluid pressure 45 may be introduced through a pipe 51 to thereby shift the shaft toward the right (Fig. 3) against the resistance of a spring 52 which normally urges the shaft toward the left extreme position shown.

The pressure fluid for operating the piston 49 on the cam shaft may be supplied from any convenient source, such as by connecting the pipe 51 to the pressure outlet side of the pump itself, and regulating the admission by any suitable 50 type of valve.

The several cams 40 are of identical form but are set at different angles on the cam shaft corresponding to the different angular setting of the crank pins of the crank shaft 15. The right 55 end of each cam (Fig. 3) is shaped to provide a single eccentric portion 53, as indicated in Figs. 1 and 7, so that, with the cam shaft in the position shown, its associated valve 37 provides communication between the bore 26 and discharge 60 passage 32 throughout the pressure stroke of its associated plunger 25, and between the bore 26 and the intake passage 35 throughout the suction stroke of the plunger 25. Under that condition of operation the pump delivers a maximum 65 volume. The opposite end of each cam is of double eccentric form, including a second eccentric portion 54, as indicated in Fig. 7, so that, when the cam shaft is shifted from the position shown in Fig. 3 into a right extreme position, 70 each cam acts upon its associated valve in such manner as to retain the same in a left extreme position throughout the pressure stroke as well as throughout the suction stroke of its associated plunger 25, so that all the liquid which has entered the bore 26 from the intake passage 35,

during a suction stroke, is returned to the passage 35 during the succeeding discharge stroke. Under that condition pump delivery is zero.

That half of the periphery of each cam, which corresponds to the suction stroke of the pressure pump plunger 25, is of uniform contour throughout the length of the cam, so that irrespective of the lengthwise shifting thereof, the bore 26 is always open to the intake passage 35 throughout the suction stroke of the plunger. The other 10 half of the periphery of each cam, which corresponds to the pressure stroke of the plunger, is of non-uniform contour and so designed as to cause the valve to open communication between the bore 26 and the discharge conduit 32 at various points in the pressure stroke of the plunger 15 25, dependent upon the lengthwise adjustment of the cam.

As previously pointed out, when the cam shaft 20 41 is in the position shown in Fig. 3, so that the cam rollers of the several valves follow the eccentric end portions 53 of their respective cams, each valve is caused to maintain communication 25 between the bore 26 and discharge passage 32 throughout the pressure stroke of the corresponding plunger 25, and the pump then delivers a maximum volume. Then as the cam shaft is shifted toward the right until each cam roller contacts with its cam in a plane corresponding to the plane of section line 8—8, a narrow lobe 30 55 (Fig. 8) on each cam causes its coating valve to effect communication between the corresponding bore 26 and intake passage 35 during the early portion of the pressure stroke of the corresponding plunger 25, so that during that portion 35 of the stroke liquid escapes from the bore 26 back into the intake passage 35, and thereafter the valve is promptly shifted to effect communication between the bore 26 and the discharge passage 35. The volume of liquid discharged 40 into the passage 35 is thus somewhat reduced. As indicated in Figs. 9 and 10, the lobe 55 of each cam becomes increasingly wider as it extends toward and finally merges into the second eccentric 45 50 55 60 65 70 75 80 85 90 95 100 105 110 115 each plunger 25, provision is made for directing the liquid from each bore 26 into the discharge passage 32 as soon as the pressure in the bore has increased to that existing in the discharge passage. Although this may be accomplished in various ways the means which will now be described is satisfactory for the purpose.

For this purpose a plunger 61 is closely fitted for lengthwise reciprocation in a bore 62 formed in the end member 38 of each valve. The plunger 61 is yieldably retained in the left end of the bore by a light spring 63, and also by pressure transmitted from the discharge passage 32 to the right end thereof through gashes 64 in the plunger and ports 65 in the valve. The left end of the plunger 61 is also exposed to the pressure in the bore 26 through ports 66 and a passage 67 in the valve. A passage 68 in the plunger 61 communicates with the passage 67 and also with radial passages 69 in the plunger. The arrangement is such that as the pressure in bore 26 increases sufficiently to overcome the pressure against the right end of the plunger 61, the plunger 61 will shift to the right (Fig. 4) until radial passages 69 communicate with ports 65, whereupon liquid from the bore 26 will pass into the discharge passage 32.

In order to guard against too rapid a change in the degree of pressure within the bore 26 the inner end of the portion 39 of each valve 37 is preferably grooved, as indicated at 70, so as to effect a gradual cutting off of communication between the intake passage 35 and bore 26, as the valve moves from a left extreme position to the intermediate position of Fig. 4, and so as to effect a gradual opening of communication between those parts during movement of the valve in the opposite direction.

Various changes may be made in the embodiment of the invention hereinabove specifically described without departing from or sacrificing the invention as defined in the appended claims.

I claim:

1. In a pump, the combination of a cylinder, an intake passage, a discharge passage, a movable valve effective in one position to effect communication between said cylinder and said intake passage and effective in another position to effect communication between said cylinder and said discharge passage, and a pressure responsive relief device contained within said valve and adapted to pass liquid into said discharge passage upon the attainment of a predetermined pressure in said cylinder irrespective of the position of said valve.

2. In a pump, the combination of a cylinder, an intake passage, a discharge passage, a movable valve effective in one position to effect communication between said cylinder and said intake passage and effective in another position to effect communication between said cylinder and said discharge passage, and a pressure responsive relief device contained within said valve and adapted to pass liquid into said discharge passage upon the attainment of a predetermined pressure in said cylinder irrespective of the position of said valve, said valve consisting of a body portion and spaced heads fixedly mounted upon said body portion.

3. In a pump, the combination of a cylinder, an intake passage, a discharge passage, a movable valve effective in one position to effect communication between said cylinder and said intake passage and effective in another position to effect communication between said cylinder and said discharge passage.

cation between said cylinder and said intake passage and effective in another position to effect communication between said cylinder and said discharge passage, and a pressure responsive relief device contained within said valve and adapted to pass liquid into said discharge passage upon the attainment of a predetermined pressure in said cylinder irrespective of the position of said valve, said valve having a bore therein, and said relief device including a member movably mounted in said bore and yielding means urging said movable member into a position adapted to close communication between said cylinder and said discharge passage.

4. In a variable delivery pump the combination of a plurality of cylinders, an intake passage, a discharge passage, valve mechanism controlling communication between said cylinders and said intake and discharge passages, plungers working in said cylinders, driving means for said plungers, means driven in timed relation with said driving means for operating said valve mechanism, said last named means being adjustable to vary pump delivery, and means contained in said valve mechanism and responsive to the pressure in said cylinders for admitting liquid therefrom to said discharge passage.

5. In a variable delivery pump the combination of a plurality of cylinders, an intake passage, a discharge passage, individual valves for the respective cylinders controlling communication between said cylinders and said intake and discharge passages, plungers working in said cylinders, means for operating said valves, said last named means being adjustable to vary pump delivery, and pressure responsive means contained in said valves and associated with each cylinder for admitting liquid therefrom to said discharge passage irrespective of the position of said valve mechanism.

6. In a pump the combination of a cylinder, an intake passage, a discharge passage, a longitudinally reciprocable valve effective in one position to effect communication between said cylinder and said intake passage and effective in another position to effect communication between said cylinder and said discharge passage, said valve being effective in an intermediate position to block communication between said cylinder and said passages, and pressure responsive means within said valve for admitting liquid from said cylinder to said discharge passage.

7. In a pump, the combination of a cylinder, an intake passage, a discharge passage, a movable valve effective in one position to effect communication between said cylinder and said intake passage and effective in another position to effect communication between said cylinder and said discharge passage, and a pressure responsive relief device contained within said valve and adapted to pass liquid into said discharge passage upon the attainment of a predetermined pressure in said cylinder irrespective of the position of said valve, said valve consisting of a body portion and spaced heads fixedly mounted upon said body portion, said valve having a bore therein, and said relief device including a member movably mounted in said bore and yielding means urging said movable member into a position adapted to close communication between said cylinder and said discharge passage.
